(57) **CLAIM**

The ornamental design for a fishing rod holder, as shown and described.

DESCRIPTION

FIG. 1 is a side perspective view of a fishing rod holder of the present invention.

FIG. 2 is a first end elevation view of a fishing rod holder depicted in FIG. 1.

FIG. 3 is a second end elevation view of a fishing rod holder depicted in FIGS. 1 through 2, rotated about a substantially vertical axis from the view depicted in FIG. 2.

FIG. 4 is a first side elevation view of a fishing rod holder depicted in FIGS. 1 through 3.

FIG. 5 is a reverse side elevation view of a fishing rod holder depicted in FIGS. 1 through 4.

FIG. 6 is a top view of a fishing rod holder depicted in FIGS. 1 through 5; and,

FIG. 7 is a bottom view of a fishing rod holder depicted in FIGS. 1 through 6.
